(57) **CLAIM**

The ornamental design for a weight-bearing lower extremity brace, as shown and described.

DESCRIPTION

This application is related to U.S. application Ser. No. 12/502,893, filed Jul. 14, 2009. The contents of each of the foregoing applications in their entirety are incorporated herein by reference.

FIG. 1 is an isometric view of a weight bearing lower extremity brace showing our new design in condition of use;

FIG. 2 is a second front isometric view of a weight bearing lower extremity brace in condition of use for the opposite leg; FIG. 3 is a rear isometric view of weight bearing lower extremity brace;

FIG. 4 is an exterior side elevational view of a weight bearing lower extremity brace;

FIG. 5 is a front elevational view of a weight bearing lower extremity brace;

FIG. 6 is an interior side elevational view of a weight bearing lower extremity brace;

FIG. 7 is a rear elevational view of a weight bearing lower extremity brace; and,

FIG. 8 is a top plan view of a weight bearing lower extremity brace.

The broken lines illustrate portions of the brace and environmental structure which form no part of the claimed design.
